UNITED STATES PATENT OFFICE.

JOHN MAXWELL AND JAMES A. ANDERSON, OF ONEIDA, NEW YORK.

DESIGN FOR A CASKET.

SPECIFICATION forming part of Design No. 33,048, dated August 7, 1900.

Application filed July 7, 1900. Serial No. 22,880. Term of patent 7 years.

To all whom it may concern:

Be it known that we JOHN MAXWELL and JAMES A. ANDERSON, citizens of the United States, residing at Oneida, in the county of Madison, State of New York, have invented and produced a new and original Design for Caskets, of which the following is a specification, reference being had to the accompanying drawing, forming a part thereof, and in which we show an isometrical view of our design complete.

As shown in the accompanying drawing, the leading or material feature of our design consists of a casket-body having its corners provided with sets or series of vertically-arranged leaf-moldings a a' , as shown. At the lower edge of the casket-body and between the series of leaf-moldings a' is an olive-leaf molding b , and the upper edge of the casket-body is provided with a similar molding b' . The central portion c of the body is plain.

The cover d is elongated cone-shaped, and the edges are provided with an olive-leaf molding d' , save at the corners, which are provided with sets of leaf-moldings e to balance the vertically-arranged leaf-molding upon the body. The casket thus constructed forms a unitary design, its corners terminating in graceful curves and the intermediate moldings of peaceful and restful design. 25 30

Having described our invention, what we claim, and desire to secure by Letters Patent, is—

The design for a casket substantially as herein shown and described. 35

In witness whereof we have hereunto set our hands this 2d day of July, 1900.

JOHN MAXWELL.

JAMES A. ANDERSON.
